UNITED STATES PATENT OFFICE.

JOSEPH H. PRICE, OF CAPE GIRARDEAU, MISSOURI.

SPARK AND THROTTLE LEVER LOCK.

1,352,693.

Specification of Letters Patent. Patented Sept. 14, 1920.

Application filed November 24, 1919. Serial No. 340,126.

To all whom it may concern:

Be it known that I, JOSEPH H. PRICE, a citizen of the United States, and a resident of Cape Girardeau, in the county of Cape Girardeau and State of Missouri, have made certain new and useful Improvements in Spark and Throttle Lever Locks, of which the following is a specification.

My present invention relates generally to devices for locking the spark and throttle levers of Ford automobiles, and more particularly to a device of this nature described and claimed in my application No. 326168, filed in the U. S. Patent Office September 25, 1919.

Among the various objects of my present improvements I aim to provide a device capable of ready adjustment to fit spark and throttle levers of slightly different spacing, and a further object is the provision of an arrangement which may be locked without the necessity of a separate pad-lock, as in my previous application.

A still further object is the provision of an arrangement wherein means are incorporated to avoid danger of defeating the purposes of a lock by unwarranted opening of the quadrant and shifting movements of the spark and throttle levers beneath the lock plate.

In the accompanying drawings illustrating my present invention:—

Figure 1 is a horizontal section through the steering post below the gear casing, illustrating the practical application of my improvements, in locked position.

Fig. 2 is a side view.

Fig. 3 is a view similar to Fig. 1 showing quadrant engaging lugs carried by the lock plate.

Fig. 4 is a rear elevation of the lock plate and quadrant of Fig. 3.

Fig. 5 is a detailed perspective view of a portion of the lock plate provided with a lever engaging lug, and,

Fig. 6 is a detailed perspective view through a portion of the quadrant and lock plate showing the application of the form of construction of Fig. 5.

Referring now to these figures, I have indicated the steering post of a Ford automobile at 10 in Figs. 1, 2 and 3. The usual gear casing 11 is shown in Fig. 2 in its normal spaced relation above the quadrant 12, over which the spark lever 13 and throttle lever 14 work in opposite directions. As

well known, the quadrant projects laterally from the steering post and has at two ends upright lugs 15 which form stops for the levers 13 and 14 when in the fully retarded and closed positions of these levers, which may, for the purposes of the present invention, be termed their "inactive" position.

As in my application above referred to, the locking mechanism includes a lock plate 16 of somewhat the shape of the quadrant 12 arranged to seat on the quadrant with one edge opposing movement of the two levers 13 and 14 when the latter are in inactive positions, and my present improvements propose that the said lever opposing edge of the lock plate 16 be provided with extended lever engaging portions 17 adjacent to the sides of the lock plate, so that in case the lock plate cannot be properly seated on the quadrant when in engagement with the levers, these extended portions 17 may be partially ground or filed away without necessitating grinding or filing of the entire lever opposing edge of the plate.

As in my application above referred to, the lock plate 16 has upper recesses 18 in which the inner portions of locking arms 19 are adapted to swing, the inner ends of these arms being journaled vertically through the plate at 20, and their outer ends being in accordance with my present improvements, provided with flatwise abutting enlargements 21 adapted to contain any suitable form of lock by which to effectively secure the same in flatwise abutting relation when closed, as in Fig. 1. This lock may include a barrel 22 having a key slot 23, as seen in Fig. 2, and in any event a self contained lock structure is contemplated for the locking arms so as to avoid the necessity of a separate pad-lock, as in my previous application.

In Figs. 3 and 4 I have shown the lock plate, which is otherwise the same as in Figs. 1 and 2, provided with spaced lower lugs 24 of the angular form, particularly seen in Fig. 4, adapted for engagement beneath portions of the edge of the quadrant 12 adjacent to the inactive positions of the levers 13 and 14, so that with the lock plate 16 seated upon the quadrant and these lugs extending beneath portions of the quadrant, any attempt to force the quadrant downwardly so that either of the levers might be pressed downwardly and shifted beneath the lock plate and between the same and the

downwardly bent quadrant, will thus be defeated.

According to Figs. 5 and 6, the possible danger of so defeating the lock may be avoided by providing the lever opposing edge of the lock plate 16, with projecting lugs, one of which is seen at 25 in Figs. 5 and 6, arranged to extend beneath the levers 13 and 14, when the latter are in inactive positions and the lock plate is properly positioned upon the quadrant so that even if the side portion of the quadrant were bent downwardly, lower movement of the levers in order to shift the same between the lock plate and the quadrant would still be prevented.

It is thus obvious that in respect to the portions of the device specifically referred to above, my present invention is an improvement over my application first referred to along lines calculated to bring about more effective, efficient results in practical use.

I claim:—

1. The combination with a steering post, control levers and quadrant on which the said levers work, of a securing member including a body plate seatable on the quadrant with one edge opposing the control levers in their inactive positions, movable arms carried by the said body plate and shiftable into embracing relation around the steering post, and means for locking the arms around the steering post, said lever opposing edge of said body plate having ex-

tensions adjacent to its opposite sides projecting beneath the levers in inactive positions for the purpose stated. 35

2. The combination with a steering post, control levers and quadrant on which the said levers work, of a securing member including a body plate seatable on the quadrant with one edge opposing the control levers in their inactive positions, movable arms carried by the said body plate and shiftable into embracing relation around the steering post, means for locking the arms around the steering post, and means carried by the body plate and arranged to prevent the control levers from being forced downwardly beneath the body plate for shifting 45 movement below the said body plate. 50

3. The combination with a steering post, control levers and quadrant on which the said levers work, of a securing member including a body plate seatable on the quadrant with one edge opposing the control levers in their inactive positions, movable arms carried by the said body plate and shiftable into embracing relation around the steering post, means for locking the arms 60 around the steering post, means carried by the body plate and arranged to prevent the control levers from being forced downwardly beneath the body plate for shifting movement below the said body plate, said 65 means being in the form of lugs projecting from the body plate, as described.

JOSEPH H. PRICE.
